CLAIM

The ornamental design for a disk drive tray bezel, as shown and described.

DESCRIPTION

FIG. 1 is a top front and left side perspective view of the disk drive tray bezel showing our new design; and,

FIG. 2 is a bottom front and left side perspective view thereof the undisclosed right side view is a mirror image.

The areas of the tray which have not been completely disclosed in FIG. 1 are understood not to be part of the claimed design.
